Attorney.

UNITED STATES PATENT OFFICE.

LINDLEY M. DOUDNA, OF CHESTER HILL, OHIO.

WELL-CURB AND WATER-DRAWER.

SPECIFICATION forming part of Letters Patent No. 255,606, dated March 28, 1882.

Application filed December 23, 1881. (No model.)

To all whom it may concern:

Be it known that I, LINDLEY M. DOUDNA, a citizen of the United States of America, residing at Chester Hill, in the county of Morgan and State of Ohio, have invented certain new and useful Improvements in Well-Curbs and Water-Drawers; and I do hereby declare the following to be a full, clear, and exact description of the invention, such as will enable others skilled in the art to which it appertains to make and use the same, reference being had to the accompanying drawings, and to letters or figures of reference marked theron, which form a part of this specification.

My invention relates to well-houses; and it consists in the construction and arrangement of its several parts, as will be hereinafter fully set forth.

In the drawings, Figure 1 is a front elevation, and Fig. 2 is a vertical section on the line $x x$.

A is the well-house, and is provided with doors a in its front.

Pivoted at b , between the sides of the house, and resting upon the bars b' , are the hinged platforms B. They are raised or lowered by the T-lever C, which extends below them, and has attached to its outer ends the rods c, which are pivoted to brackets b^2 upon the under sides of the platforms, as shown. A handle,

c' , is attached to the upper end of the lever, and a keeper, c^2 , confines it closely to the side of the house, as shown.

In operation it will be seen that by raising the lever C the platforms B will be carried upwardly upon their hinges, and will allow the well-buckets to pass between them. When let down upon the bars b' a narrow recess is left between the platforms to permit the passage of the bucket-rope.

In the upper portion of the well-house is arranged the raising and lowering device for the buckets. It consists of the grooved pulley D, provided with an axle-box, d , around the inner end of which is formed the beveled gear d' , as

shown. The pulley is journaled upon the axle d^2 , which projects horizontally from the bracket d^3 , secured to the top of the supporting-bar E, as shown. Projecting upwardly from the opposite end of the bracket is the lug d^4 , through which is journaled the crank-shaft F. The inner end of this shaft has secured to it the beveled-gear wheel f, which engages with the gear d' of the wheel D, as shown. Upon the outer end of the shaft is a crank, f' .

G is the bucket-rope. It passes over the wheel D, as shown, and is held in place by the keepers $g g$, pivoted to the top of the bar E. Upon each side of the wheel H H are the buckets.

I is the pulley-brake. It passes through the bar E, is bent at right angles behind it, is bent again, and passes back through the bar E, and its end is adapted to enter recesses i in the face of the pulley D.

In operation, as a bucket in its ascent reaches the under side of the platforms B it will raise them up and pass through them, after which they will drop back upon the bar b' .

If it is desired to hold the bucket at any point in its ascent or descent by engaging the brake I with the pulley D, it can be readily accomplished.

What I claim is—

1. In a well-house, the pivoted shelves B, operating in combination with the T-lever C and connecting-rods c, substantially as and for the purposes specified.

2. The pulley D, its axle-box d , and gear d' , operating in combination with the axle d^2 , bracket d^3 , lug d^4 , crank-shaft F, and gear f, substantially as shown and described.

In testimony whereof I affix my signature in presence of two witnesses.

LINDLEY M. DOUDNA.
